DIE FOR FORMING SLIDERS OF SEPARABLE FASTENERS

Davis Marinsky, Bronx, N. Y., assignor to White-hall Patents Corporation, Bronx, N. Y., a corporation of New York

Application February 28, 1939, Serial No. 258,929

5 Claims. (Cl. 18—42)

This invention relates to a novel and improved construction and arrangement of core and die members, more particularly where such members are used in casting a slider for separable fasteners or the like. The invention will be best understood from the following description and the annexed drawing, in which I have shown a selected embodiment of the invention and in which:

10 Fig. 1 is a sectional view through a die structure made according to my invention, the section being substantially on the line 1—1 of Fig. 2 of the drawing showing part of the construction broken away.

15 Fig. 2 is a sectional view substantially on the line 2—2 of Fig. 1.

Fig. 3 is a view similar to Fig. 1 but looking in the opposite direction and showing the die members and core parts of the die mechanism separated and illustrating a casting stripped from the core members.

Fig. 4 is a detail sectional view on the line 4—4 of Fig. 3.

Fig. 5 is a detail sectional view on the line 5—5 of Fig. 3, and

Fig. 6 is a longitudinal sectional view through the casting shown in Fig. 3, on the line 6—6 of said figure.

This application constitutes a continuation in part of my prior application, Serial No. 129,319, filed March 6, 1937, and which has now matured into Patent No. 2,181,142, granted November 28, 1939, and is directed to the die structure for forming castings generally of the type and kind in accordance with the method taught in said prior application.

For the purpose of clarity, I have shown in Figs. 3 and 6 of the drawing a casting to be formed by the die structure, and it will be understood that this casting is simply illustrative of the type and kind of castings which can be formed.

The slider body 10 as shown comprises top and bottom walls 11 and 12 joined at one end by a connecting web or post 13. The walls 11 and 12 have inturned spaced side flanges 14 and 15, and the top wall is provided with a finger piece supporting loop 16 cast integrally therewith. The above structure forms a slider body which has two diverging channels separated by the connecting web 13 at the wide end of the slider and defined by the spaced flanges, as will clearly appear in Fig. 3 of the drawing.

15 At 17 and 18 are shown the die members of

the die structure and at 19 and 20 are shown the core members of the die structure.

Adjacent surfaces of the die members 17, 18 are provided with impressions 21 which define the outer surfaces of the walls 11, 12 of the resulting slider. The impressions 21 are provided centrally with ribbed portions 22 which partially form the space between adjacent surfaces of the inturned flanges 14 and 15 as will clearly appear in Fig. 2 of the drawing. Adjacent surfaces of 10 the die parts 17 and 18 are also provided with registering recesses 23 which collectively form the loop 16 on the resulting casting. Between adjacent abutting surfaces of the die parts is formed a gate or admission passage 24, note Fig. 15 2, whereby casting material may be injected under pressure into the impression or mold cavity in forming the casting from a nozzle or discharge partially shown at 25 in Fig. 2 of the drawing.

At this time it is well to point out that the 20 sliders may be cast from any desired die casting material and may be cast from thermoplastic materials such for example as cellulose acetate. It will be understood that the nozzle 25 is brought into registering position with the gate 24 when 25 the die parts and core members are in firm engagement with each other.

The core part 19 may be said to be fork-shaped or yoke-shaped in form; that is to say, it is provided with an elongated aperture or recess 26 30 opening through one end thereof dividing the core part into separate members 27, which thus form arms of the fork. The members 27 are provided with projecting ribs 28 on outer edges thereof which cooperate with the ribs 22 in 35 completing the space between adjacent inturned flanges 14 and 15 as clearly seen in Fig. 2 of the drawing. The members 27 terminate at their upper ends in shoulder portions 29 which form the ends walls 30 of the slider body.

At the base of the aperture or recess 26 is a curved end wall or fork crotch 31 which forms the rounded end 32 of the connecting web 13. The ends 33 of the members 27 are adapted to seat on shoulders 34 formed on the core part 20, 45 the core part having a projecting tongue 35 which fits snugly in the aperture 26 and has at its free end a V-shaped recess 37 which forms the V-end 38 of the web 13 as will clearly appear from a consideration of Figs. 1 and 3 of the drawing. Thus the crotch 31 and end 37 of the tongue are properly spaced and shaped to form the web or post 13, the stops or shoulders 34 limiting the movement of the core members towards each other to insure proper spacing of the crotch 31 55

and end 31. Shoulder portions 39 are also provided on the core part 20 to form the end walls 40 of the resulting casting and between the shoulders 39 and the shoulders 34 the sides of the core part 20 are provided with ribs 41 which form continuations of the ribs 28.

In the operation of the dies and core members, suitable means are provided for controlling the relative movement thereof in a properly timed relationship, and in operation the core parts 19 and 20 are first moved into engagement with each other when the die parts 17, 18 are in open position, after which the die parts are closed. While the dies and cores are held in firm engagement with each other, the casting material is injected under pressure into the impression formed around and between the parts, after which the die parts 17 and 18 are separated, the cores operating as means for ejecting the casting from said die parts. The core parts are then separated, the casting being movable with the part 19, after which the casting is then stripped from said part as is illustrated in Fig. 3 of the drawing.

25 In the drawing, to clearly illustrate the operation of the dies and core members employed, a particular type of slider has been shown, and the impression between said dies and core members conforms with the contour of this particular slider and represents only one of innumerable impressions which may be employed. In other words, a slider of any desired shape may be formed by dies having the structural features herein disclosed, providing the contour of the resulting casting permits separation of the die and core parts as indicated.

It will also be apparent that the structural features are not of necessity limited to dies for casting sliders, but may be employed to equal 40 advantage in casting other objects between movable dies when it is desired that the resulting casting have at least partially closed channels extending in a plane perpendicular to the line of travel of the dies.

45 Having fully described my invention, what I claim as new and desire to secure by Letters Patent, is:

1. A device for casting a hollow article having spaced walls connected by a web or post, 50 comprising dies having inner surfaces thereof shaped to form the outer surfaces of said walls, a core member having a fork shaped to extend between said walls, and a second core member having a tongue slidable between the arms of said fork, the crotch of said fork and the end of said tongue being spaced apart and shaped to define the outer surface of said web or post.

2. In a device for casting a hollow article having spaced walls connected by a web or post, a

core comprising two members, one of said members having a fork and the other member having a tongue slidable between the arms of said fork, the crotch of said fork and the end of said tongue being spaced apart and shaped to define the outer surface of said web or post. 5

3. In a device for casting a hollow article having spaced walls connected by a web or post, a core comprising two members, one of said members having a fork and the other member having a tongue slidable between the arms of said fork, the crotch of said fork and the end of said tongue being spaced apart and shaped to define the outer surface of said web or post, and a stop on one of said members engaging the other member to limit their movement towards each other. 10 15

4. In a device for casting a slider for separable fasteners having diverging channels defined by top and bottom walls connected by a web between the channels and having the edge portions of 20 said walls provided with inturned spaced flanges to define the outer boundaries of said channels; two dies movable into and out of engagement with each other and having inner surfaces which, when the dies are in engagement with each other, define the outer surfaces of said walls and flanges, a core comprising two members movable towards and away from each other in a direction at right angles to the direction of movement of said dies, one of said members having a fork and the other member having a tongue slidable between the arms of said fork during said relative movement of the members, means stopping the movement of said tongue towards the crotch of said fork, said 30 crotch and the end of said tongue, when said movement is thus stopped, being spaced apart and shaped to define the outer surface of said web and the arms of said fork having surfaces shaped to define the inner surfaces of said walls 40 and flanges and to cooperate with said inner surfaces of the dies to define all surfaces of said walls and flanges. 35

5. In a device for casting a slider for separable fasteners having diverging channels defined by top and bottom walls connected by a web between the channels, a core comprising a member having spaced arms forming a fork, the outer surfaces of said arms converging towards one 45 end of the member and said arms being spaced apart at that end, the inner surfaces of said arms being parallel to each other, and a second core member having a tongue slidable between said arms and having surfaces engaging said inner surfaces of the arms, the end of said tongue and the crotch of said fork being spaced apart when the members are in operative position and being shaped to define the outer surface of said web. 50 55
